PICK WHEEL OPERATED LOOM STOP MOTION MECHANISM

Ludlum H. Rockwell, Bloomsburg, Pa.

Application August 4, 1950, Serial No. 177,654

4 Claims. (Cl. 139—339)

1

This invention relates to loom stop motion mechanisms and more particularly to a stop motion switch operated by a loom pick wheel to stop the loom whenever the pick wheel fails to make a full forward step.

It is among the objects of the invention to provide a stop motion switch mechanism for a loom which will immediately stop the motion of the loom whenever the loom pick wheel and associated mechanism fail to complete a full forward rotational step, thus protecting the woven fabric against irregularities occasioned by running two or more yarn threads in the same space in the warp of the fabric, which mechanism can be easily installed on an existing loom adjacent the loom pick wheel and operated by movement of the pick wheel, which is ineffective to stop the loom except upon failure of the pick wheel to complete a forward rotational step, which is fully adjustable for accurate operation and to accommodate the mechanism to various looms and pick wheels, and which is simple and durable in construction, economical to manufacture, easy to install, and positive and effective in operation.

Other objects and advantages will become apparent from a consideration of the following description and the appended claims in conjunction with the accompanying drawings wherein:

Figure 1 is an elevational view of a fragmentary portion of a loom showing a loom pick wheel and a stop motion switch mechanism illustrative of the invention operatively mounted on the loom adjacent the pick wheel;

Figure 2 is a top plan view of the loom fragment and stop motion switch mechanism illustrated in Figure 1, portions being broken away and shown in cross section;

Figure 3 is a side elevational view on an enlarged scale of the stop motion switch mechanism;

Figure 4 is a top plan view of the stop motion switch mechanism illustrated in Figure 3;

Figure 5 is a cross sectional view on the line 5—5 of Figure 3;

Figure 6 is a cross sectional view on an enlarged scale on the line 6—6 of Figure 3;

Figure 7 is a cross sectional view on the line 7—7 of Figure 3;

Figure 8 is a side elevational view of a modified form of stop motion switch mechanism;

Figure 9 is a top plan view of the mechanism illustrated in Figure 8; and

Figure 10 is a side elevational view of a still further modified form of stop motion switch mechanism.

2

With continued reference to the drawings, and particularly to Figures 1 and 2, the fragmentary portion of the loom illustrated includes a loom frame 10 provided with suitable bearings, as indicated at 11, for a pick wheel and pick spool or cylinder shaft, a pick wheel 12 mounted on one end of the shaft at the outer side of the frame 10, a handwheel 13 mounted on the same end of the shaft and disposed outwardly of the pick wheel 12 for manually rotating the pick wheel and pick cylinder to take up slack in the cloth or fabric on the loom, a pick wheel rotating arm 14 pivotally mounted intermediate its length on the pick wheel shaft, a link 15 connected between one end of the arm 14 and the loom drive mechanism to impart angular, oscillating movement to the arm 14, a pawl 16 pivotally mounted on the other end of the arm 14 and engageable with the ratchet teeth 17 on the periphery of the pick wheel to impart step by step rotational movement to the pick wheel, and a locking pawl 18 pivotally mounted on the frame at a location spaced from the pawl 16 and engageable with the pick wheel ratchet teeth 17 to hold the pick wheel against reverse rotational movements.

As long as the pick wheel operating mechanism is all in perfect operating condition and there is no material wear or looseness, the pawl 16 will advance the pick wheel a full step each time the arm 14 is moved by the link 15 and the locking pawl 18 will drop behind successive ratchet teeth permitting no back movement of the pick wheel. However, if the pawl 16 fails to advance the pick wheel the full forward step, the locking pawl 18 will not clear the ratchet tooth with which it is engaged and drop behind this ratchet tooth, thus permitting the pick wheel to turn back to its original position when the arm 14 is returned in its oscillating movement. If the loom continues to operate under these conditions, the shuttle will be passed a second time through the same space in the warp, laying two yarn threads side by side in the same space and producing an irregularity in the cloth. If the pick wheel should repeatedly fail to advance, the shuttle will, of course, continue to lay yarn threads in the same space since the warp does not advance unless the pick wheel rotates. The passing of the shuttle repeatedly through the same space in the warp will necessitate shutting down the loom while the extra yarn threads are removed and may even then result in an irregularity in the cloth and may even cause a serious jamming of the loom.

With the present invention in operation, if the

pick wheel fails to advance the full step each time it is moved by the arm 14, the loom will be immediately stopped so that only one yarn thread will be laid in the same space in the warp and no irregularity in the fabric will be produced.

In the form of the invention illustrated in Figures 1 to 7 inclusive, a rectangular U-shaped bracket 20 is provided in its closed end with a centrally located aperture 21 and is pivotally mounted on the loom frame 10 adjacent the pick wheel 12 by a bolt 22 which extends through the aperture 21 and through a registering aperture provided in the loom frame.

At the open end of the bracket 20 the bracket legs 23 and 24 are turned outwardly and apertured to receive the bolts 25 and 26 respectively. The outwardly turned portion 27 of the leg 24 is extended and provided with a longitudinally extending slot 28 spaced from the bolt 26. The edge of the bracket portion 27 adjacent the pick wheel is provided with a notch having an inclined side 29 extending from a location adjacent the bolt 26 to a location adjacent the end of the slot 28 nearest the bolt 26 and with a side 30 which extends from the end of the side 29 adjacent the slot 28 substantially perpendicular to the edges of the bracket portion 27.

A detent 31 is adjustably mounted on the bracket portion 27 by a screw 32 extending through an aperture in the detent and through the elongated slot 28. This detent is tapered in a direction toward the associated pick wheel and has a beveled end portion 33 which engages the ratchet teeth 17 of the pick wheel and limits pivotal movements of the bracket 20 about the bolt 22. The elongated slot 28 provides for adjustment of the detent along the bracket portion 27 to compensate for different pick wheel diameters and different sizes and spacing of the pick wheel ratchet teeth.

A lever 34 is provided near one end with an aperture receiving the bolt or screw 26 which bolt pivotally connects the lever at such one end to the bracket portion 27 adjacent the leg 24. Near its opposite end the lever 34 is provided with an aperture receiving the bolt 25, and a switch plate 35 is disposed at the side of the lever 34 remote from the outwardly bent portion 36 of the bracket arm 23 and provided with an aperture which also receives the bolt 25.

The aperture in the bracket portion 36 through which the bolt 25 extends is in the form of an elongated slot 37 extending transversely of the bracket portion 36 and the bolt 25 is provided at one end with a head 38 bearing against the side of the bracket portion 36 remote from the lever 34 and with an enlarged portion 39 adjacent the head and disposed within the slot 37 of the bracket portion 36. The end of the enlarged portion 39 remote from the head 38 provides a bearing shoulder for the adjacent side of the lever 34 and a nut 40 is threaded onto the bolt and bears against the adjacent side of the plate 35, a lock washer 41 being preferably interposed between the nut 40 and the plate 35.

With this arrangement, the lever 34 and plate 35 can be locked together in adjustment position between the nut 40 and adjacent end of the enlarged portion 39, but the enlarged portion of the bolt will still be freely slideable in the slot 37 in the bracket portion 36 so that the plate 35 and lever 34 can move together about the axis of the pivotal connection provided between the lever and the bracket portion 27 by

the bolt 26 within the limits provided by the length of the slot 37.

The plate 35 is provided with a notch 42 in its edge adjacent the pick wheel 12 and a detent 43 at the side of the notch remote from the bolt 25 which detent rests upon the ratchet teeth 17 of the pick wheel and drops into the spaces between adjacent ratchet teeth as the pick wheel is rotated, the slot 37 providing the necessary freedom of movement of the plate 35 and detent 43 for this purpose and the detent being constrained to follow the contour of the outer surfaces of the ratchet teeth by the weight of the plate 35 and of the adjacent end of the lever 34.

An internally screw threaded socket 44 is mounted on the plate 35 near the adjacent end of the lever 34 and is electrically insulated from the plate. An electrical conductor 45 leads from this socket and a fixed electric contact 46 is adjustably threaded through the socket 44 to constitute one contact of the stop motion switch.

An L-shaped switch arm 47 is pivotally mounted on the plate 35 by a screw 48 extending through registering apertures in the switch arm and the plate, the aperture in the plate being adjacent the inner end of the detent 43 and the aperture in the switch arm being disposed intermediate the length of the latter. One leg 49 of the switch arm carries a movable contact 50 which is complementary to the fixed contact 46 and engageable therewith when the switch is closed. A tension spring 51 connected between the switch arm 47 and the plate 35 resiliently holds the switch arm in position such that the contact 50 is spaced from the contact 46 and the switch is opened.

The switch arm 47 is provided at the side of the pivot screw 48 remote from the arm 49 with an extension 52 which extends along the detent 43 and projects from the edge of the detent 43 adjacent the notch 42.

As is clearly illustrated in Figure 1, the switch mechanism is mounted on the loom so that the detent 43 and switch arm extension 52 are opposed to the radially disposed or pawl engaging faces 53 of the ratchet teeth 17.

Referring now to Figure 1, it will be apparent that if the pawl 16 rotates the pick wheel a full step so that the pawl 18 leaves the tooth with which it was engaged at the beginning of the rotational movement of the pick wheel and drops behind the pawl engaging face 53 of the succeeding tooth as the pawl 16 reaches the end of its pick wheel rotating movement, the pick wheel will be held by the pawl 18 against any reverse rotational movement and will be rotated in successive steps by the pawl 16. However, if the pawl 16 should fail to rotate the pick wheel through a full forward step, the pawl 18 will not drop over the edge of the successive tooth, but will remain on the outer surface of such tooth and, when the pawl 16 reaches the limit of its pick wheel rotating movement and returns to its original position, the pick wheel will rotate in a reverse direction back to its original position and will fail to advance the warp in the loom.

When the pick wheel is advanced, even a small amount, by the pawl 16, the detent 43 of the plate 35 and the switch arm extension 52 will drop down behind the pawl engaging face of the ratchet tooth on which these elements were resting at the beginning of the rotational movement of the pick wheel. If there is no subsequent reverse rotation of the pick wheel the switch comprising the contacts 46 and 50 will remain

open and the operation of the loom will not be interrupted. However, should the pick wheel move in a reverse direction when the pawl 16 returns, the adjacent ratchet tooth will contact the extension 52 of the switch arm and move the switch arm about the pivot screw 48 against the force of spring 51 in a direction to bring the movable contact 50 into electrically conductive engagement with the fixed contact 46. When the switch has been fully closed, further reverse rotation of the pick wheel will be stopped by the detent 43 so that the switch parts will not be bent or damaged.

The switch is connected in circuit to a suitable electromagnetic relay which may be connected either directly or indirectly into the motor circuit for the loom driving motor so that operation of the loom will be discontinued immediately upon closing of the stop motion switch.

After the loom has been stopped the loom operator will make the necessary adjustments in the pick wheel rotating mechanism to render the pawl 16 effective to advance the pick wheel a full step each time the mechanism operates. As soon as the ratchet tooth pressure on the switch arm extension 52 has thus been relieved the loom can be restarted and will continue to operate until the pick wheel again fails to make a complete forward rotational step.

The pivot screw 48 for the switch arm 47 is also electrically insulated from the lever 34 and the switch arm itself is electrically insulated from this lever to avoid the danger of any accidental short circuit between the switch arm 47 and the socket 44. As illustrated in Figure 6, a flat plate 54 of electrically insulative material is interposed between the socket 44 and the switch arm 47 and apertured to receive the pivot screw 48 and the socket stem 55. Sleeves 56 and 57 of electrically insulative material surround the screw 48 and stem 55 respectively in the apertures provided therefor in the plate 35 and nuts 58 and 59 are threaded on the screw 48 and the stem 55 respectively at the side of the plate 35 remote from the insulating body 54. As the switch arm 47 makes a ground contact with the pick wheel of the loom, the single wire 45 is sufficient to complete the switch circuit, this wire being connected to the socket 44 by the terminal 60.

In the modified arrangement illustrated in Figures 8 and 9, the bracket 20, described above, is replaced by an elongated bar 61 which is secured at some convenient location along its length to the frame of the loom in a manner to position the stop motion switch mechanism contiguous to the periphery of the pick wheel of the loom.

A notch 62 is provided in the pick wheel adjacent of the bar 61 intermediate the length of the latter and a tongue or detent 63 is secured to the bar at one end of this notch for positioning the bar relative to the pick wheel of a loom.

Otherwise, the mechanism is substantially the same as that illustrated in Figures 1 to 7 inclusive and described above and includes the lever 34 pivotally connected at one end to the bar 61 by a bolt or screw 26, the bolt 25 adjustably connecting the plate 35 to the free end of the lever 34 and extending through the slot 37 in the adjacent end of the bar 61. The plate 35 carries the fixed contact socket 44 and fixed contact 46 and the switch arm 47 pivotally connected to the plate by the pivot screw 48. The 75

plate 35 is provided with the detent 43 and the switch arm 47 with the extension 52 engageable by a ratchet tooth on the pick wheel to close the switch in the above described manner.

5 In the further modified arrangement shown in Figure 10, the construction is substantially the same as that illustrated in Figures 8 and 9 and described above, except that the lever 34 is omitted, the detent 63 is adjustably connected to a bar 64, corresponding to the bar 61, and the plate 35 is adjustably connected directly to the bar 64 at a location spaced from the detent 63.

15 In this arrangement, the lever 64 will be pivotally mounted on a supporting structure, such as the loom frame so that the plate 35 can move up and down as the pick wheel rotates. The detent 63 is provided with an elongated, transversely extending slot 65 receiving the bolt or 20 screw 32 so that the detent can be adjusted longitudinally of the bar 64. The lever 35 is provided with a longitudinally extending slot 66 receiving the bolt 25' so that the plate can be adjusted both longitudinally and angularly 25 of the bar 64. In this case, the bolt 25' may be a simple bolt without the shoulder providing enlarged portion 39 of the bolt 25. Otherwise, the operation of the form of the invention shown in Figure 10 is the same as that described above in connection with Figures 1 to 9 inclusive.

30 The invention may be embodied in other specific forms without departing from the spirit or essential characteristics thereof. The present embodiments are, therefore, to be considered 35 in all respects as illustrative and not restrictive, the scope of the invention being indicated by the appended claims rather than by the foregoing description, and all changes which come within the meaning and range of equivalency of the 40 claims are, therefore, intended to be embraced therein.

What is claimed is:

1. In combination with a loom having a frame, a pick wheel journaled on said frame and provided with peripheral ratchet teeth, means engageable with the pick wheel teeth for imparting step by step rotational movement to said pick wheel, means engageable with said pick wheel teeth as each step is completed to hold said pick wheel against return movement, pick wheel operated switch mechanism for stopping the loom motion upon failure of said pick wheel to complete a full rotational step comprising a bar pivotally mounted on the loom frame and disposed adjacent the periphery of said pick wheel, a detent on said bar engaging said ratchet teeth and dropping into the spaces between adjacent teeth as said pick wheel rotates, a fixed contact carried by said bar adjacent said detent, a switch arm pivotally mounted on said bar and carrying a movable contact complementary to said fixed contact, and a spring connected between said bar and said switch arm resiliently urging said movable contact away from said fixed contact, said arm including a portion extending along said detent and projecting from one side of the latter for engagement by said ratchet teeth to move said movable contact into engagement with said fixed contact upon reverse rotational movement of said pick wheel.

2. In combination with a loom having a frame, a pick wheel journaled on said frame and provided with peripheral ratchet teeth, means engageable with the pick wheel for imparting step by step rotational movement in one di-

rection thereto, and means engageable with said pick wheel as each step is completed to hold said pick wheel against rotational movement in the opposite direction; pick wheel operated switch means for stopping the loom motion upon failure of said pick wheel to complete a full rotational step comprising a switch assembly including a movable switch arm extension resiliently biased in one direction and effective to close the switch when moved in the opposite direction, and means supporting said switch assembly adjacent the periphery of the pick wheel for movement of said switch arm extension in the switch closing direction by said pick wheel upon movement of the latter in said opposite direction.

3. In combination with a loom having a pick wheel and mechanism rotating said pick wheel step by step in one direction, stop motion means comprising means adjustably mounted on the loom in engagement with the pick wheel and a switch actuated by the last mentioned means

upon rotational movement of said pick wheel in the opposite direction to discontinue operation of the loom.

4. In combination with a loom having a pick wheel and mechanism rotating said pick wheel step by step in one direction, stop motion means comprising means adjustably mounted on the loom in engagement with the pick wheel and a normally open switch closed by the last mentioned means upon rotational movement of said pick wheel in the opposite direction to discontinue operation of the loom.
